UNITED STATES PATENT OFFICE

EDWARD O. HERMANN, OF MILL VALLEY, CALIFORNIA, ASSIGNOR TO COBB CONNECTOR COMPANY, OF LOS ANGELES, CALIFORNIA, A CORPORATION OF ARIZONA

TRAIN PIPE COUPLER

Application filed October 18, 1927. Serial No. 226,878.

My present invention relates to means for automatically connecting the air and steam pipes of two adjacent railway cars and my object is to devise a connecting means of the above type which will simultaneously and automatically couple the steam pipe, air brake train pipe and signal line pipe and maintain a tight joint under all ordinary running conditions.

Another object of my invention is to provide a novel form of support which will permit sufficient movement to avoid a break in the connections due to train movements.

A further object of my invention is to provide a novel form of centering means for my train pipe coupler which will maintain it centrally of the car when disconnected so that, when approached by a cooperating coupler, it will align therewith.

Another object of my invention is to provide means whereby the pneumatic pressure within the train pipe line may be utilized to securely hold the cooperating couplers together and seal the joints when the same are in operation.

A further object of my invention is to provide automatic means whereby the above-mentioned pneumatic pressure may be released upon an accidental break in the train pipe to thereby permit the couplers to readily separate and thus avoid damage thereto.

Another object of my invention is to provide means whereby my coupler can be readily opened up so as to facilitate inspection and repair to the normal wearing parts.

A further object of my invention is to provide in a coupler of the above type, an auxiliary or emergency air relief valve in the coupler head which will be opened up, should the couplers be accidentally separated, as when the train parts, due to pulling out of the coupler head to relieve the train brake pipe of pressure and thereby set the brakes.

Other objects and advantages will appear as the description, taken in connection with the accompanying drawings, proceeds.

For a better understanding of my invention, reference should be had to the accompanying drawings in which I have shown a preferred embodiment of my invention. It

is to be understood that in adapting the same to meet the many conditions that may arise, various changes in the form, proportion and minor details of construction may be resorted to without departing from the nature of the invention.

In the drawings,

Fig. 1 is a side elevation showing a train pipe coupler in accordance with my invention connected below the coupler head, 60

Fig. 2 is a front elevation, partially in section, of the elements shown in Fig. 1 and taken along line II—II,

Fig. 3 is a plan view of the train pipe coupler and sections through its supporting members, 65

Fig. 4 is a side elevation of the coupler projected from Fig. 3 with the guide member removed,

Fig. 5 is a vertical sectional view of the coupler taken along line V—V of Fig. 3,

Fig. 6 is a horizontal sectional view taken along line VI—VI of Fig. 4,

Fig. 7 is a plan view, partially in section, of the centering means and coupler taken along line VII—VII of Fig. 1, 75

Fig. 8 is a sectional view through the train pipe coupler taken along line VIII—VIII of Fig. 4,

Fig. 9 is a side elevation projected from Fig. 8 and showing the valve operating means, and 80

Fig. 10 is a sectional view taken along line X—X of Fig. 8.

Fig. 11 is a partial sectional view of the centering mechanism taken along line XI—XI of Fig. 7. 85

Referring now particularly to the drawings the numeral 10 may generally designate an ordinary car coupler, the interlocking heads of which are mounted on drawbars 11 of any ordinary construction. It will be understood that the drawbars 11 and the coupler 10 are so placed as to always effect interlocking of the coupler elements within all possible variations of position, including the relative vertical displacement of the two coupler heads; and it will also be understood that my device is hung so that it will 100

properly interlock under all conditions in which car couplers will interlock.

By referring to Figs. 1 and 2 of the drawings, it will be seen that my improved train pipe coupler is supported from the car framing 12 by a pair of brackets 13. The brackets 13, in turn, engage and support a centering mechanism 14 which is to be hereinafter more fully described. Extending 10 from the centering mechanism 14, I provide a pair of shoulders 15 which project downwardly from the centering mechanism 14 and engage the rear end of my improved 15 coupler body, which in the drawings is designated by the numeral 16. The shoulders 15, in conjunction with the centering mechanism 14, tend to hold the coupler body 16 in its normal position against longitudinal, transverse and angular displacement, but is 20 so designed that the movements necessary in rounding curves, etc., will not be interfered with.

In addition to the shoulders 15, I provide a link 17 which is carried by the centering 25 mechanism 14 and extends downwardly where it engages and supports the weight of the coupler body 16. The link 17 is secured to the coupler body 16 at its center of gravity and is connected through a swivel joint 18 to rollers 19 which roll freely longitudinally in the centering mechanism 14 as will hereinafter appear. Adjacent the point where the shoulders 15 overlap the coupler body 16, I provide a pair of cheeks or plane surfaces 30 20 against each of which two rollers 21 engage. The rollers 21 are carried by a follower block 22 which is spring pressed outwardly from the shoulders 15 by means of springs 23. The rollers 21, by reason of the 25 springs 23, serve to hold the coupler body 16 in an advanced position so that the engaging coupler will be fully seated before the cars have been completely coupled and at the same time permit the aforementioned 30 freedom so essential in couplers of this type.

Before passing on to a more detailed description of the coupler body 16, attention should be called to the disconnecting mechanism which I have provided in my device. 35 Depending from one of the brackets 13 upon a pivotal support 24, is a stop 25. The stop 25 is freely movable toward the right as viewed in Fig. 1, but is prevented from swinging to the left by a lug 26. In line with 40 the stop 25, I provide a lever 27 which is mounted upon a manual release rod 28 and operates an automatic coupler releasing means which is to be described more fully later in this description. Connected to the 45 lever 27, I show a link 29 which is attached at its opposite end to a latching means 30. The provision of these features is to prevent damage to or dropping of one of the coupler bodies, should a drawbar pull out. In the 50 event of such a contingency, the lever 27 will

engage the stop 25 and further movement in this direction will cause it to rotate upon its axis and release the coupler securing means. At the same time, as a result of the link 29, the latching means 30 will also be released and permit the coupler to open and thus prevent any possible damage to the engaging parts of the cooperating couplers. In these figures of the drawings, I have also illustrated the usual manual coupler releasing mechanism and have purposely shown one of the type which is operated from its underside so as to show the adaptability of my invention to cars having this type of coupler. This releasing mechanism comprises the 55 usual hand-operated bar 31 with its offset arm 32 connected to the pin releasing trigger 33. In the completed installation, it is proposed to connect the bar 31 and the manual release rod 28 together so that both the train coupler and the pipe coupler can be released by a single operation from either side of the car.

Attention is now directed to Figs. 3, 4, 5 and 6 of the drawings, wherein I have illustrated in detail some of the more important features of the pipe coupler head. Upon an inspection of Fig. 3, it will be seen that the coupler body 16 is provided with an extending tongue 35 and a hinged guide member 36 which cooperate with the corresponding parts of a similar coupler when in operation. The tongue 35 has projections 37 and 38 which extend at right angles thereto and form a holding means in conjunction with the latch 30 for the guide member 36, the projections 37 and 38 being provided with grooves into which the latching means 30 engages and thus rigidly maintains the guide member in place. The guide member 36 is hinged at 39 to the coupler body 16 and is provided with a flared end portion 40 from the top and bottom edge of which project respectively additional guiding means 41 and 42. The member 36, by reason of the hinge 39, can, when the latch 30 is released, be swung outwardly as shown in this figure of the drawings, so that inspection and repair can be conveniently made. At the hinge 39, the guide member 36 is provided with a shoulder 43 which engages the plane surface plate 20 so that when the guide member 36 is moved to either of its extreme positions, it will be held in such position.

In carrying out this feature, I have taken advantage of the springs 23 by bringing the shoulder 43 against the plate 20 so that off-center pressure will be brought to bear upon the shoulder 43 and thereby maintain the guide member 36 as described above in either of its extreme positions. The guide member 36, in addition to the above, is provided with a spring 44 which is adapted to engage the projecting tongue 35 of a corresponding coupler and cause it to slide into contact with the corresponding tongue. The tongue 35 is pro-

- vided with a wearing plate 45 which extends over the end thereof and which is readily replaceable so that as the same wears out, it may be replaced by a new one. This wearing plate 45 extends back along the tongue 35 to a point substantially in line with the outlet ports and is tapered down so as not to interfere with the proper action of the gaskets arranged therein.
- 5 In addition to the plate 45, I have provided a movable plate 46 which is hinged at the point 47 so that it has a limited outward movement, which, when properly brought into play, as will be hereinafter set forth, will operate to force the cooperating ports of the respective tongues into intimate and effective contact with each other.
- 10 In Fig. 4, the tongue 35 is shown with the guide member 36 entirely removed so as to expose the engaging face of the coupler to view and show the location of the signal air, brake air and steam line ports or outlets which I have designated respectively by the numerals 48, 49 and 50. These ports are provided with gaskets 51 which project slightly beyond the surface and engage with corresponding gaskets on the cooperating coupler. The wearing plate 45 is here shown as having portions which project between the above gaskets. These projections are tapered down and disengage corresponding projections on the cooperating coupler when the corresponding gaskets are substantially adjacent each other and thus do not interfere with the sealing of the ports in the manner to be presently described.
- 15 In connection with this view of the drawings, attention is directed to the plugged holes 54, 55 and 56 which I have provided to receive the usual train pipe connectors during the transition period, or in other words, during that period of time when the cars of the system are being equipped with my improved coupler.
- 20 A steam trap 57 of the usual type, through which condensed steam or water may drain from the coupler head, is also shown in this view. Projecting out of the extreme end of the tongue 35 are three valve rods or stems which I have designated respectively from top to bottom by the numerals 58, 59 and 60. The valve stems 58 and 59 are connected to valves 61 and 62 which control respectively the signal air and brake air pipe lines and the stem 60 controls a valve 63 in the train steam pipe line. The valves 61, 62 and 63 will be discussed more fully in connection with Fig. 5 of the drawings, but before passing from Fig. 4, attention is called to a movable abutment 64 which is normally in line with and engages the approaching valve stem 59 of a cooperating coupler. The abutment 64 is normally held against a rest 65 by a spring 66. A pin 67 projects from the far side of the abutment 64 (as shown in Fig. 6) which is engaged by a lever 68 attached to the release rod 28 and when the release rod 28 is rotated, the abutment will be raised upwardly out of engagement with its cooperating valve stem 59 and permit the stem to move outwardly from the tongue 35 to thereby release the pressure responsive sealing or holding means which is to be later discussed. While the lever 68 is secured to the rod 28 and normally operated thereby, it can also be raised in emergency by a finger 52 formed integral with lever 27.
- 25 By referring to Fig. 5, it will be seen that the coupler body 16 is divided longitudinally into three compartments 70, 71 and 72, and that each of these compartments is divided into two chambers by partitions 73, 74 and 75, into which the aforementioned valves 61, 62 and 63 are respectively mounted. The chambers on the port side of the valves 61, 62, and 63 will be referred to hereinafter as the port chambers 76, 77 and 78. The compartments 70, 71 and 72 are provided respectively with inlets 79, 79' and 79'' to which the usual universal pipe joining couplings are attached and the compartment 71 also contains an emergency valve 69 which is operated by the lever 27, as will be pointed out in connection with a description of Figs. 8, 9 and 10 of the drawings. The valve 69 exhausts into an opening extending longitudinally of the coupler head between the brake air and steam compartments. The port chambers 76 and 78 are substantially alike, each having respectively valve seats 80 and 81 and stuffing boxes 82 and 83, through which the valve stems 58 and 60 project. The stuffing boxes 82 and 83 form a guide for the outer end of the valve stems 58 and 60 and a second guide means is provided in the other side of the valves 61 and 63 by means of bosses 84 and 85. Surrounding the valve stems 58 and 60 between the bosses 84 and 85 and the valves, I show springs 86 and 87 which maintain the valves 61 and 63 normally closed.
- 30 Referring now to the central chamber 77 and its valve 62, together with its cooperating mechanism, which is further illustrated in Fig. 6, it will be seen that the chamber 77 is provided with a cylindrical lining 88 having a valve seat 89 which cooperates with the valve 62. It will also be seen that the valve stem packing in this chamber is carried by a piston 90 which is movable longitudinally within the cylinder 88. The piston 90 is actuated by the brake pipe air pressure in one direction and by a spring 91 in the reverse direction. The spring 91 is seated against an abutment 92 through which the valve stem 59 projects. The cylindrical lining 88 has a pair of slots 93 at diametrically opposite points and the piston 90 carries a yoke 94 having stub shafts 95 which extend through these slots. Each of the stub shafts 95 carries rollers 96 and 97 which cooperate respec-

tively with raceways 98 and 99, as shown in Fig. 6. The raceways 99 are carried by the movable plate 46 and are arranged at an angle to the raceways 98, so that when the 5 piston 90 is moved outwardly in response to air pressure, the plate 46 will be pressed outwardly where it will engage its cooperating guide member 36 and thus exert a pressure to hold the parts in a tight or sealed fit.

13 In conjunction with the piston 90, I provide within the cylindrical lining 88 and above the head of the piston, an auxiliary valve 100. The valve 100 is provided with a guiding support 101 which maintains the 15 valve concentric with the stem 59 and permits it to move axially therealong. Between the valve 100 and the piston 90, I insert a stationary stop 102 and interposed between this stop and the valve 100, is a spring 103, 20 which tends to hold the valve 100 against a pin 104 projecting through the stem 59. This valve 100 cooperates with a by-pass port 105 which extends diametrically through the valve seat 89 and communicates with the atmosphere and, when opened, relieves the piston 90 of pressure so that it can release the holding means when the valve 62 is closed by 25 movement of the abutment 64.

For a better understanding of the construction of the centering mechanism 14, reference should be had to Fig. 7 of the drawings in connection with the showing of Fig. 1. In Fig. 7, the upper bracket 13 is shown in section and on the other side a centering mechanism, the bracket spring housing is shown in section. Enclosed in the housing, which I shall designate by the numeral 106, I show a spring 107. The spring 107 holds the centering mechanism 14 in its normal position against stops 108 and permits it to move forward a limited distance when tension is exerted between the couplers. The housings 106 are cut away at their inner bottom side to receive flanges 109 upon a frame 45 110 formed as a part of the centering mechanism, so that the same can operate freely therein as the spring 107 is compressed. The front part of the frame between the flanges 109 is formed into a Z-shaped cross section 50 111 (as shown in Fig. 11) and arranged centrally between the flanges 109, I provide a slot or opening 111 through which pivoted arms 112 and 113 extend. The arms 112 and 113 are pivoted to the centering mechanism by a pivot bolt 114, upon which the movable parts of the centering mechanism also pivot. The 55 arms 112 and 113 are located between an extension 115 integral with the shoulders 15 and a cover plate 116 and extend through 60 the opening 111 where they engage stops 117 formed upon the cover plate 115.

Arranged between the arms 112 and 113, I show a spring 118 which tends to hold the arms apart and against the stops 117. From 65 the above, it will be evident that the exten-

sion 115 and the cover plate 116 together with the coupler will move as a unit about the pivot 114 and that the Z-shaped frame portion between the flanges 109 will remain substantially stationary. It is to facilitate this 70 relative movement between the frame and the coupler unit and to relieve the pivot 114 of transverse stress that the front portion of the frame is made in Z-shape cross section. Co-operating with this Z portion of the frame I 75 provide a pair of rollers 119 upon the cover plate 116 near the sides thereof. These rollers 119 rest upon the inner web of the frame and support the weight of the movable parts in conjunction with the pivot 114. Only one 80 of the rollers 119 is shown in the drawings as the cover plate is broken away to show other features at the point where a second roller 119 would be shown. Other and similar rollers 120 are also provided which engage the underside of the outer web of the frame at radially displaced points in line with the rollers 119 and serve to prevent upward movement of the centering mechanism with respect to the frame. In connection 85 with this figure of the drawings, it should be noticed that the stops 117 (previously referred to) are located radially in line with the ends of the opening 111 and cooperate therewith in a manner to be pointed out in 90 describing the operation of my device.

Attention is now directed to Figs. 8, 9 and 10 of the drawings, wherein I have shown enlarged views of the aforementioned emergency or train pipe relief valve. Fig. 8 is a vertical section through the center line of the valve 69 and it shows a port 121 leading from the compartment 71 to the atmosphere. The valve 69 and the lever 68 are both secured to the shaft 28 and move therewith when it is 100 rotated, due to hand operation. The valve 69 also carries a member 122 having a projection 123 which cooperates with a finger 124 carried by a sleeve 126 to which the lever 105 27 is secured, so that, upon movement of the lever 27, the lever 68 and the valve 69 will 110 also rotate and thereby raise the abutment 64 and open the valve 69 to exhaust the train pipe. The valve 69 is formed as a hollow 115 plug and is pressed into its seat by a spring 127 interposed between the valve 69 and a plate 128.

In Fig. 10 it will be seen that the valve 69 has two ports 129 and 130 diametrically opposite each other which form a passageway 120 therethrough.

The operation of the supporting means which I have provided for my coupler is as follows: With the parts in the position shown in Figs. 1 and 2, the coupler body 16 125 will be held slightly in advance of its normal position by the springs 23 and when engaged by a cooperating coupler, the springs 23 will be compressed so as to exert a pressure tending to hold the two coupler bodies together. 130

As the cooperating coupler approaches, its tongue 35, as well as the tongue 35 of the illustrated coupler, will be guided by the guide members 36 into their respective positions so that their respective ports will align. During this operation, the springs 23, through the followers 22 and rollers 21, will also absorb any shock and because of the mounting as provided upon the link 17, the rollers 19 will permit the coupler heads considerable freedom so that they will become seated in their normal operating position.

In the event that the train couplers should be loose upon the car and, as a result, the pipe couplers should be pulled outwardly, the springs 107 will be compressed and the lower part of the support, including the centering mechanism, will be allowed to move outwardly without danger of the pipe coupler ports being disaligned. However, should this outward movement become excessive, the stop 25 will become effective and engage the lever 27. If this forward movement is sufficient to move the lever 27, it will automatically operate the coupler releasing mechanism and open the valve 69. This will permit the couplers to pull apart without being damaged. From the above, it will be seen that the coupler body is suspended entirely upon the link 17 and is only guided or steadied by the rollers 21 which engage the face plate 20.

Attention is now directed to the centering aspect of my present form of support. The frame 110 is held within the brackets 13 against pivotal movement, but it can slide longitudinally therein upon the flanges 109 so as to permit the couplers to move in and out with respect to the car frame 13. The frame 110 carries the pivot 114 and thus provides a pivotal support for the shoulders 15, the extension 115 and the cover plate 116, so that they will move as a unit about the pivot 114 and thus permit the couplers to remain in alignment when rounding curves. This aspect of my invention is best shown in Fig. 7 of the drawings and it operates as follows: When the parts are in the position shown, centrally of the frame 110, the spring 118 will be fully extended and the pivoted arms 112 and 113 will each engage their respective end of the slot 111. When the arms 112 and 113 are in this position they will also engage the adjacent stops 117 carried by the extension 115 and, as a result, the parts will be held centrally of each other. This is because the spring 118, by reason of its engagement with the ends of the slot 111, can exert no pressure in either direction upon the stops 117. If, now, the tongue 35 is moved in the direction of the arrow at the left, the lower stop 117 will engage the pivoted arm 113 and move it away from its engagement with the end of the slot 111, and as a result, the spring 118 will be compressed against the other pivoted

arm 112 which is held against the other end of the slot 111, which is always stationary with respect to this radial movement. The upper stop 117 will not interfere with this operation because it is free to move away from the pivoted arm 112. After the tongue 35 is again released, it will be returned to its normal position by the spring 118 acting through the pivoted lever 113 which bears against the lower stop 117. Should a reverse movement be imparted to the tongue 35, the pivoted arm 112 would leave its end of the slot 111 by reason of pressure exerted upon it by the upper stop 117 and the pivoted arm 113 would engage its end of the slot 111 and the tongue 35 would be permitted to move in the reverse direction by compressing the spring 118. When the tongue is again released, it would immediately return again to its normal position under the influence of the spring 118, as previously described.

The operation of the other features of my invention can best be described in connection with the showing in Figs. 4, 5 and 6 of the drawings. As the cooperating tongues 35 of two adjacent couplers come together, the wearing plates 45 will engage and slide over each other and thus protect the gaskets 51, 52 and 53. When the above gaskets are substantially in alignment, the engaging wearing plates will have passed over each other and, by reason of the tapering off in the ends thereof, the gaskets will be permitted to engage each other. At a point just before the gaskets and the respective ports align, the valve rods 58, 59 and 60 will engage the end of the throat formed between the tongue 35 and the guide member 36 and will be pushed back into the tongue 35, thereby opening the valves 61, 62 and 63, and establishing a circulating passageway between the couplers through the ports 48, 49 and 50. It should be noted here that the end of the throat, above referred to, is provided with two fixed shoulders or abutments, against which the valve stems 58 and 60 engage and that the movable abutment 64 presents a surface in alignment therewith, against which the valve stem 59 engages, so that each of the valve stems is caused to move an equal distance. When the two engaging couplers are fully seated, the valves 61, 62 and 63 will be completely opened. During this operation, the valve stem 59, by reason of the abutment 64, will be moved to the right as viewed in Figs. 5 and 6. This will open the valve 62 and permit the spring 103 to seat the auxiliary valve 100 and close the by-pass port 105. In connection with the valve 100 it should be noted that it is provided with an opening through its center and thus it does not interfere with a free circulation of air through the valve 62. As the brake pipe pressure builds up, the piston 90, which is freely movable within the cylinder 88, will be forced outwardly in

each of the couplers, the pressure therebehind being equalized in the adjacent tongue and against the adjacent piston 90. This movement of the pistons 90 will carry the rollers 96 and 97 along their cooperating raceways 98 and 99 and force the movable plate 46 outwardly against its engaging guide member 36 to thereby exert a pressure thereagainst and force the aligned gaskets into a tight or sealed fit with each other, where they will remain as long as the couplers are operating.

From the above, it will be seen that after the coupler heads are engaged, additional means are operated to securely press them into tight contact with each other at the gaskets, where they will be held by air pressure until released by a subsequent operation which I shall now describe. Normally, a coupler of this type should remain tightly coupled as long as the cars are coupled together and I have therefore provided manual means which may be operated simultaneously with or ahead of the train coupler releasing mechanism, so that the train pipe coupler securing means will be released before or simultaneously with the release of the car couplers. This means is in the form of a manually operated release rod 28 which, as previously stated, can, if desired, be operated in conjunction with the train coupler release rod 31. When the release rod 28 is operated it will raise the abutment 64 out of alignment with the valve stem 59 and permit the valve 62 to close in response to the action of a spring 62'. This movement of the valve stem 59 will carry the auxiliary valve 100, by reason of the pin 104, away from the by-pass port 105 and permit the pressure above the piston 90 to exhaust into the atmosphere. The piston 90 will then move to the right in response to the spring 91 and thus carry the rollers 96 and 97 along the trackways 98 and 99 so as to permit the movable plate 46 to move inwardly and relieve the coupler heads of the sealing pressure exerted thereby. The couplers can then be parted without any danger to the parts. Under normal operating conditions, the release rod 28 will be operated before the couplers are placed under tension and when the rod 28 is so operated, the couplers will be completely released so that they can be pulled apart as the cars separate without any strain being exerted upon the coupler supports.

Should the cooperating couplers be under tension when the release rod 28 is operated, the springs 107 will permit sufficient movement of the couplers with respect to the cars to prevent danger while the pneumatic release aspect of my device is operating. In the event that the pneumatic releasing features of my device should fail for any reason, as for instance when a car traction coupler pulls out, the stop 25 upon the bracket 13 will engage the lever 27 and cause it to turn

the rod 28 and raise the lever 68, thereby moving the abutment 64 and also causing the emergency valve 69 to open, as previously described. In addition to the above operation, the lever 27 will, by reason of the link 29, pull the latch 30 out of engagement with the arms 37 and 38 and permit the guide arm 36 held thereby to move outwardly and thus mechanically release the couplers. It should be noted here that the link 29 is connected to the latch 30 by an open slot so that it will pull free thereof. It should be understood that this latter releasing feature of my device is only effective under extreme conditions and is primarily intended to operate where danger would result to the couplers or their supports, should they not be parted.

Having thus described my invention, what I claim and desire to secure by Letters Patent is—

1. In a train pipe coupler system, a coupler head having ports adapted to cooperate with similar ports upon a cooperating coupler head, a fluid pressure responsive means adapted to force said heads into sealed engagement with the ports of one head in register with the ports of the other head, a valve adapted to control the flow of fluid to said pressure responsive means, means for automatically opening said valve to admit fluid pressure to said pressure responsive means when said ports are in alignment, and manually operable means for rendering said valve opening means inoperative.

2. In combination with a train pipe coupler, a supporting member extending from the car frame having a pivot and an arcuate guide rail portion, a second member adapted to carry a coupler head secured to said supporting member by said pivot and having means cooperating with said guide rail whereby it will freely move therealong about said pivot, and means tending to maintain said second member and the coupler head carried thereby centrally of said supporting member.

3. In a train pipe coupler, a supporting member extending from the car frame having a pivot and an arcuate guide rail portion of Z-shape cross section, a second member adapted to carry a coupler head secured to said supporting member at said pivot, rollers on said second member engaging opposite sides of said guide rail, an opening through the vertical web of said guide rail, a pair of arms mounted upon said pivot extending through said opening and engaging stops upon said second member beyond said guide rail, and a spring between said arms tending to hold them into engagement with the ends of said opening and said stops, whereby said coupler will be held centrally of said supporting member.

4. In combination with a train pipe coupler of the type having interlocking ele-

- ments, a support for the coupler head, means whereby the coupler head may move with respect to said support when under tension, fluid pressure means for holding said coupler head in cooperative relation with a similar coupler head, and automatic means carried by said coupler adapted to be operated by said support to release said pressure responsive holding means when the movement of said coupler with respect to said support becomes excessive, to thereby permit a separation of the cooperating coupler heads. 5
5. In a train pipe coupler system, a coupler head having ports adapted to cooperate with similar ports upon a cooperating coupler head, a fluid pressure responsive means adapted to force said ports into sealed engagement, a valve adapted to control the flow of fluid to said pressure responsive means, means for automatically opening said valve to admit fluid pressure to said pressure responsive means when said ports are in alignment, manually operable means for rendering said last-mentioned means inoperative, 15 and means for automatically operating said manual means when said coupler head is placed under excessive tension. 20
6. In a train pipe coupler, the combination of a coupler head having an extending portion with ports therein adapted to project into a recess of a corresponding coupler head, a member extending lengthwise along said projecting portion adapted to move outwardly therefrom and engage the side of the recess of the cooperating coupler to hold the ports of the couplers into sealed engagement, and means for automatically moving said member outwardly when said ports are 25 in alignment. 30
- 40 7. In combination with a train pipe coupler head, a link forming a one-point suspension for said coupler head, a plane vertical surface upon said coupler head extending at right angles to its axis, and yielding abutments engaging said plane surface at vertically and horizontally displaced points, whereby said head is yieldingly held in a horizontal position upon said link. 45
8. In a train pipe coupler head having ports adapted to align with similar ports upon a cooperating coupler head, a partition in said coupler head between the ports and a fluid supply, a valve in said partition adapted to open when said ports are in alignment, means carried by said coupler for forcing said ports intimately together, and a piston within said coupler head on the port side of said valve adapted to cooperate with and move said means when said valve is opened. 55
- 60 9. In a train pipe coupler system, the combination of a pair of cooperating coupler heads having corresponding ports adapted to align and form a conduit for fluid therethrough, a hinged guide means upon said coupler heads for guiding and holding them into cooperating relation, a locking means for securing said hinged guide means and means for actuating said locking means whereby said guide means can be unlocked and moved away from said heads to permit inspection and repair thereof. 70
10. In a train pipe coupler system, the combination of a pair of cooperating coupler heads having corresponding ports adapted to align and form a conduit for a fluid therethrough, valves within said coupler heads mounted upon stems which project out of said heads adapted to control the flow of fluid through said ports, abutments upon each of said coupler heads against which said valve stems abut arranged to open said valves when the coupler heads are engaged, means whereby one of said abutments may be moved out of engagement with its cooperating valve stem and means for closing the valve of said stem after such movement and while said coupler heads are engaged. 75
11. In a train pipe coupler system, the combination of a pair of cooperating coupler heads having corresponding ports adapted to align and form a conduit for a fluid therethrough, valves within said coupler heads mounted upon stems which project out of said heads adapted to control the flow of fluid through said ports, abutments upon each of said coupler heads against which said valve stems abut arranged to open said valves when the coupler heads are engaged, a plate carried by each of said coupler heads extending substantially over the outside surface thereof adapted to be moved outwardly therefrom and into engagement with the cooperating coupler to force the aligned parts of the coupler heads into sealed engagement, and a fluid responsive means adapted to force said plate outwardly when said couplers are engaged and said valves opened. 85
12. In a train pipe coupler system having coupler heads with ports in the sides thereof of which slide into alignment with each other, gaskets in said ports projecting slightly beyond the coupler face, a wearing plate arranged in advance of said gaskets on each head and presenting a surface raised with respect to the gaskets, said wearing plate being tapered off at said gasket whereby the adjacent gasket will engage with an abutting movement rather than with a sliding movement. 90
13. In a train pipe coupler system, the combination of a pair of cooperating coupler heads having corresponding ports adapted to align and form a conduit for a fluid therethrough, valves within said coupler heads mounted upon stems which project out of said heads adapted to control the flow of fluid through said ports, abutments upon each of said coupler heads against which said valve stems abut arranged to open said valves when the coupler heads are engaged, a fluid pres- 100

sure operated expansion device in each of said heads adapted to operate when said valves are opened to force the ports of the cooperating coupler heads into sealed engagement, said expansion device including a fixed plate, bearing port orifices, a movable plate, bearing cooperating port orifices and means actuated by a train line valve stem, to cause one of said plates to expand to intimately contact with and to effect continuity in said ports, means whereby one of said abutments may be moved out of engagement with its cooperating valve stem and means for closing the valve of said stem after such movement and while said coupler heads are engaged, whereby said fluid pressure device may be rendered inoperative and thus facilitate disengagement of said coupler heads.

14. In a train pipe coupler system, the combination of a pair of cooperating coupler heads having corresponding ports adapted to align and form a conduit for a fluid therethrough, valves within said coupler heads mounted upon stems which project out of said heads adapted to control the flow of fluid through said ports, abutments upon each of said coupler heads against which said valve stems abut arranged to open said valves when the coupler heads are engaged, a fluid pressure operated expansion device in each of said heads adapted to operate when said valves are opened to force the ports of the cooperating coupler heads into sealed engagement, said expansion device including a train line valve stem actuated piston and means actuated by said piston to effect expansion of a movable plate into intimate contact with a cooperating member, means whereby one of said abutments may be moved out of engagement with its cooperating valve stem and means for closing the valve of said stem after such movement and while said coupler heads are engaged, whereby said fluid pressure device may be rendered inoperative and thus facilitate disengagement of said coupler heads.

15. In a train pipe coupler system, the combination of a pair of cooperating coupler heads having corresponding ports adapted to align and form a conduit for a fluid therethrough, valves within said coupler heads mounted upon stems which project out of said heads adapted to control the flow of fluid through said ports, abutments upon each of said coupler heads against which said valve stems abut arranged to open said valves when the coupler heads are engaged, a fluid pressure operated expansion device in each of said heads adapted to operate when said valves are opened to force the ports of the cooperating coupler heads into sealed engagement, said expansion device including a train line, valve stem, a piston movable with said valve stem, rollers journalled on said piston, a fixed plate, a movable plate

having angularly positioned raceways thereon, said rollers being adapted to move over said raceways to cause outward movement of said movable plate to cooperate with said fixed plate to effect continuity of said conduit, means whereby one of said abutments may be moved out of engagement with its cooperating valve stem and means for closing the valve of said stem after such movement and while said coupler heads are engaged, whereby said fluid pressure device may be rendered inoperative, and thus facilitate disengagement of said coupler heads.
